UNITED STATES PATENT OFFICE.

EDWARD A. LEET, OF NEW YORK, N. Y., ASSIGNOR TO MIRRORPHON TALKING MACHINE COMPANY, INC., OF BROOKLYN, NEW YORK.

PHONOGRAPH-HORN.

1,361,164.

Specification of Letters Patent.

Patented Dec. 7, 1920.

Application filed February 5, 1920. Serial No. 356,482.

To all whom it may concern:

Be it known that I, EDWARD A. LEET, a citizen of the United States, residing at New York, in the county and State of New York, have invented certain new and useful Improvements in Phonograph-Horns, of which the following is a full, clear, and exact specification.

This invention relates to phonographs, and particularly to horns or amplifying passages therefor, and has for its object to provide a horn and tone arm which will produce a louder, purer and clearer tone than previous constructions, and at the same time to reduce the cost of manufacture of such parts so that the phonograph may be sold to the public for less money than those now on the market.

The invention contemplates the use of ordinary commercial strawboard for the construction of the horn and tone arm, I having discovered that when made of such material, which is non-resonant, rigid and adapted to vibrate, the tone is greatly improved. While strawboard is preferred, any other non-resonant, rigid and vibrating material may be employed without departing from my invention. By non-resonant is meant the inability to give out vibrations audible to the human ear when the material is brought into contact with sound vibrations. By using several thicknesses of the material, with or without corrugations, great rigidity may be obtained, and this rigidity gives added strength to the echoes which occur during the passage of the sound waves through the instrument, thereby producing a greater volume of sound. By corrugating or otherwise breaking up the inner surface of the horn and tone arm, more echoes are produced during the passage of the sound waves therethrough, thereby further increasing the volume of sound. The construction of the instrument of non-resonant, rigid material, as explained, gives the necessary strength or intensity to the volume of sound, while the desired size or fullness, which must be present with the strength or, intensity in order to produce the maximum increase in volume, may be obtained by coating the sound conducting passages of the horn and tone arm with a resilient substance, such as shellac, wet glue or liquid belt dressing which will remain sticky or

viscid for an indefinite period. A further and very important advantage of the present construction is that the entire sound passage is free from anything which might audibly vibrate during the passage of the sound waves therethrough, so that the resulting quality of tone is an exact reproduction in timbre of the original voice, instrument, combination of voices or instruments, or whatever made the sound recorded on the record.

The invention will now be described in connection with the accompanying drawings, which constitute part of this specification, and then more specifically defined in the claims at the end of the description.

In the accompanying drawings, wherein similar reference characters are used to designate corresponding parts throughout the several views:

Figure 1 is a front elevation of a phonograph constructed in a preferred manner and containing a horn and tone arm made substantially in accordance with this invention.

Fig. 2 is a central vertical section taken on the line II—II of Fig. 1.

Fig. 3 is a horizontal section on the line III—III of Fig. 2.

Fig. 4 is a horizontal section taken on the line IV—IV of Fig. 2.

Fig. 5 is a detailed vertical section of the combined horn and tone arm drawn to a larger scale, and

Fig. 6 is a section on the line VI—VI of Fig. 4, showing the connection of the sound box to the tone arm.

In Figs. 1 to 4, inclusive, of the drawings, 1 designates a cabinet having its walls, partitions and doors preferably made of strawboard, each of said walls, etc., being made up of two thicknesses of smooth strawboard 2 and 3 separated by a layer of corrugated strawboard 4 in order to obtain the desired rigidity combined with lightness. The number of thicknesses or layers of strawboard, as well as the formation of said layers may, however, be varied to suit requirements.

The cabinet may be divided about midway of its height by a transverse horizontal partition 5, the space below said partition being used preferably for the storage of records and for that purpose fitted with

any suitable form or rack or the shelves 6. Access may be had to said storage compartment 7 by means of doors 8 which may be hinged to the opposite sides of the cabinet 5 and fitted with knobs 9. In the upper portion of the compartment 7, just below the partition 5, there are placed two drawers 10 and 11 which have knobs or pulls 12 and may be used for the storage of needles or 10 styluses, sound boxes, or the like. The drawer 11 may be made shallower than the drawer 10, and behind said drawer 11 may be arranged a box 13, Fig. 2, for holding the motor (not shown). The crank 14 for 15 winding the motor is passed through the side of the cabinet and may be unscrewed from the winding spindle in the usual way.

The space in the cabinet above the partition 5 is preferably divided into two compartments by a partition 15 extending rearwardly from the front of the cabinet near the top thereof downwardly and rearwardly to the partition 5 near the back of the cabinet. The compartment 16 below and in 20 front of said partition 15 contains the turntable 17 mounted on the projecting spindle 18 of the motor, and the tone arm 19 which is a part or continuation of the horn 20 and has the sound box 21 attached thereto in any 25 suitable manner, as by the tubular extension 22 of said sound box frictionally engaging a rubber gasket 23 fitted in an opening 24 in the end of the tone arm. The portion of the tone arm which merges into the horn extends 30 through a slot 25 in the partition 15. The compartment 16 may be closed by doors 26 suitably hinged or otherwise mounted on the cabinet and provided with hand knobs 27. When the doors are closed all sound of 35 scraping of the needle on the record is shut in so that it is not audible to the listener during the playing of a record.

One or more electric lamp bulbs 28 may be supported in the upper portion of the 40 compartment 16, Fig. 2, so as to throw light on the turntable and facilitate the changing of records and needles. Said lamp or lamps may be supplied with electric current from any suitable source in any suitable manner, 45 as by a dry battery 29 through circuit wires 50 containing a suitable switch 31.

As best shown in Fig. 5, the horn and tone arm are made integral or in one piece, the 55 walls thereof being composed of two thicknesses or layers 32 and 33 of smooth strawboard spaced apart by transverse members 34 to form an air chamber 35, and an inside 60 layer of corrugated strawboard 36. The inner surfaces of said horn and tone arm are coated at 37 with the resilient substance already mentioned. The provision of the air 65 chamber or cushion around the horn and tone arm increases the desirable resiliency of said parts as well as improves the non-resonant quality thereof.

The horn and tone arm are supported to swing freely both vertically and horizontally by a double hinge compensating device 38 comprising vertical members 39 and 40 hinged together by a flexible strip of cloth 70 41, or the like, a pair of horizontal members 42 and 43 hinged together by a similar flexible strip 44, and a cradle 45 embracing the lower portion of the horn. The vertical member 39 is secured to the back of the cabinet in the compartment 46 back of the partition 15, while the horizontal member 43 carries the horn embracing cradle 45. The vertical member 40 and horizontal member 42 are rigidly connected together preferably 75 by the diverging arms 47. A resilient support 48, preferably a coiled spring, is attached at one end to the mouth of the horn and at the other end to the vertical member 40 for yieldingly retaining the upper end 80 portion of said horn in proper position and so that it may follow the movements of the lower portion thereof and the tone arm on the double hinge support.

The compartment 46 may have additional 90 walls 49 within the main walls of the cabinet 1 to increase the rigidity and resiliency of this compartment. In the walls of the cabinet above said additional walls 49 openings 50 are formed for the escape of the 95 sound waves, and said openings are preferably covered on the inside with silk as at 51, Fig. 2. A piece of similar material 52 is also stretched across the top of the compartment 46 above the openings 50. Said silk coverings 100 are designed for masking the horn and excluding dust.

Within the top of the compartment 46 there is a ledge 53 to which a dome shaped cover 54 is hinged at 55 and on which it is 105 supported when closed. The silk piece 52 may also be attached to this ledge, preferably to the under edge thereof. At one side of said ledge a rack 550 may be provided to co-operate with a prop 56 pivoted to the cover 110 and adapted to be adjusted with its free end in any one of the notches of the rack for supporting the cover at any desired angle as suggested in dotted lines in Fig. 2. In Fig. 4, 57 indicates the usual speed controlling lever 115 for the motor, said lever projecting from below the edge of the turntable.

The cabinet structure and the compensating double hinge support for the horn are claimed in separate applications filed here- 120 with.

Having thus described my invention, what I claim as new and desire to secure by Letters Patent of the United States is:—

1. A phonograph horn having a smooth 125 wall and a corrugated wall arranged with the ridges between its corrugations against the inner surface of said smooth wall.

2. A phonograph horn having spaced 130 inner and outer smooth walls and a cor-

rugged wall arranged with the ridges between its corrugations against the inner surface of the inner smooth wall.

3. A phonograph horn having spaced 5 inner and outer walls, and a corrugated lining for the inner wall.

4. A phonograph horn having spaced inner and outer walls, and a corrugated lining for the inner wall coated with a resilient substance for the purpose specified.

5. An integral horn and tone arm for

phonographs having spaced inner and outer walls and a corrugated lining for the inner wall.

6. An integral horn and tone arm for 15 phonographs having a smooth wall and a corrugated wall arranged with the ridges between its corrugations against the inner surface of said smooth wall.

In testimony whereof I have signed my 20 name to this specification.

EDW. A. LEET.
